PACKING

Fletcher H. Field, Detroit, Mich., assignor to
Rhodes Metallic Packing Company, Detroit,
Mich., a corporation of Michigan

Application November 3, 1930. Serial No. 493,202

10 Claims. (Cl. 154—45.5)

This invention relates to improvement in metallic packing employed for packing rods, shafts and the like.

One of the principal objects of this invention is to provide a metallic packing having high heat resisting properties.

Heretofore it has been customary in constructing metallic packing and the like to employ Babbitt metal but in practice it has been found that packing formed of Babbitt metal is practically incapable of resisting temperature much in excess of 450° F. In accordance with the present invention I propose constructing my packing of a metal having high heat resisting properties and capable of resisting temperatures up to approximately 1,000° F.

One metal which I have found suitable and to meet the conditions specified above, is magnesium alloy. Another, is an alloy of copper and lead. In fact, the present invention contemplates forming the packing of magnesium alloy; an alloy of copper and lead, or any other non-abrasive alloy having high heat resisting properties.

My present invention also contemplates the provisions of an outer protecting cover for the packing formed of braided magnesium or magnesium alloy wire.

My invention also contemplates a packing having a core formed of magnesium or magnesium alloy wire around which asbestos is braided.

The essentials of my invention will be made more apparent as this description proceeds, especially when considered in connection with the accompanying drawing wherein.

Figure 1 is a fragmentary elevational view illustrating one form of packing constructed in accordance with my invention;

Figure 2 is a sectional view taken substantially on the plane indicated by line 2—2 in Figure 1;

Figure 3 is a view similar to Figure 1 of a slightly modified form of construction, and

Figure 4 is a sectional view taken substantially on the plane indicated by line 4—4 in Figure 3.

Referring now more particularly to Figures 1 and 2 it will be noted that there is illustrated a core 10 which extends centrally longitudinally of the packing and this core may be made of rubber or asbestos and be constructed in the form of a helix or a braided member or in any other desired manner and of any desired material. It is desirable, however, that the core be relatively compressible.

The reference character 11 indicates an enclosing or surrounding layer of metal constituting the body of the packing. This surrounding body may be formed of magnesium, magnesium alloy,

an alloy of copper and lead, or any other non-abrasive alloy capable of withstanding high temperatures or in other words, having high heat resisting properties.

The body 11 may be constructed in any preferred or desired manner as, for instance, from strips of material which are longitudinally folded and interfolded and compressed in interlocked position. When forming the body of the packing of metallic strips, these strips may be coated on one or both sides with a lubricant such as oil or graphite or both or any other preferred or desired lubricant. When strips thus coated are interfolded and pressed in interlocking position, an inherently resilient structure results and in use the lubricant is slowly freed so that the packing becomes practically self-lubricating.

In Figures 1 and 2 the reference character 12 indicates an outer protecting cover of preferably flexible material such as fabric or the like which is woven around the structure in any well known manner.

Instead of the usual fabric protecting cover, I may make a covering of braided magnesium or magnesium alloy wire, such an arrangement being contemplated by the present invention.

In Figures 3 and 4, I have illustrated an outer protecting cover 13 formed of braided magnesium or magnesium alloy wire.

This protecting cover might also be formed of wire made of an alloy of copper and lead or of some other non-abrasive alloy having high heat resisting properties.

In Figures 3 and 4, the body 11 of the packing is formed of any of the materials and in any of the ways suggested in connection with the former construction shown in Figures 1 and 2.

In Figures 3 and 4 there is shown a core 14 composed of a plurality of lengths of magnesium or magnesium alloy wire 15 enclosed in a protecting casing or cover 16 of asbestos which could be woven around the magnesium wires 15 in the same manner in which the outer protecting covers are usually produced.

A packing constructed in accordance with this invention is not only flexible and resilient, but has high heat resisting properties and may be employed to advantage in many places where Babbitt metal packings are unsatisfactory.

While several forms of construction of my invention have been illustrated and described herein, the illustrated forms of construction should be considered as suggestive only, reservation being made to make such changes and modifications

as may come within the purview of the accompanying claims.

What I claim as my invention is:

5. A metallic packing comprising a core, a surrounding layer of a non-abrasive metal alloy having high heat resisting properties, and a protecting cover of braided magnesium alloy wire.
6. A metallic packing comprising a core formed of magnesium wire surrounded by a protecting cover of asbestos, and a surrounding layer of a non-abrasive metal alloy having high heat resisting properties. 80
7. A metallic packing comprising a core formed of a plurality of lengths of wire containing magnesium, a cover of asbestos woven around said core, a body surrounding said core and formed of strips of material which are longitudinally folded and interfolded, said strips of material containing magnesium, and a covering on said body of braided wire containing magnesium. 85
8. A metallic packing comprising a core containing magnesium and a surrounding layer of a non-abrasive metal having high heat resisting properties. 90
9. A metallic packing comprising a core, a surrounding layer of a non-abrasive metal having high heat resisting properties, and a protective cover containing magnesium. 95
10. A metallic packing comprising a core, a surrounding layer of a non-abrasive metal alloy containing magnesium and having high heat resisting properties, and a protective cover containing magnesium. 100
